UNITED STATES PATENT OFFICE

2,146,503

REMOTELY CONTROLLED ARC FOR
SEARCHLIGHTSFrank R. House, Baldwin Harbor, N. Y., assignor
to Sperry Gyroscope Company, Inc., Brooklyn,
N. Y., a corporation of New York

Application February 26, 1935, Serial No. 8,263

10 Claims. (Cl. 177—329)

This invention relates to arc lamps, especially of the high intensity type for use in high power searchlights. The invention especially concerns a means for quickly striking and quickly extinguishing or occulting the arc so as to increase its usefulness for signalling purposes. According to my invention, I provide a simple means for quickly extinguishing the arc and for quickly striking the arc without breaking the main arc supply, and which therefore may be remotely operated through comparatively small wires. The searchlight may therefore be readily operated from a distance and may be used to flash signals without the use of the cumbersome iris or other shutters commonly employed for this purpose.

Referring to the drawings,

Fig. 1 is a side elevation, partly in section, of the lamp unit of a high power searchlight, with my invention applied thereto.

Fig. 2 is a front elevation of the same.

Fig. 3 is a detached view of the occulter disc.

Fig. 4 is a wiring diagram of the lamp.

I have illustrated my invention as applied to a high intensity type lamp unit having a positive electrode holder 1 and a negative electrode holder 2, the positive carbon being shown at 3 and the negative carbon at 4. Suitable means are provided for feeding each electrode, the negative being normally fed in response to the voltage drop across the arc, and the positive being rotated and fed so as to maintain the positive crater at the focus of the reflector 22, or other projector. Both of said mechanisms are well known in the art and need not be described in detail. The voltage coil for controlling the negative feed is represented at 5 in the wiring diagram and the positive feed is controlled by contacts 6 (actuated from an arc position responsive device such as a thermostat or third electrode), which contacts control a coil 7 regulating the rate of feed and rotation of the electrode as known in the art,—for instance, the patent to Hall, No. 1,679,718, dated August 7, 1928.

The rotating and feeding motion is generated, in this instance, in the lamp box 8, represented in dotted lines in Fig. 4, the power being supplied by motor M, and is transmitted to the positive holder through universal shaft 9 and gearing 10 and 11, the latter rotating a sleeve 12 in the positive holder which carries the feed rollers 13, by which the electrode is fed from a planetary gear 14 which rolls around a fixed gear 15, and suitable intermediate transmission gearing 16. The arrangement is such that the positive electrode is normally fed at somewhat less rate than

its normal consumption, but when the thermostat operates, the rate is increased to above the normal consumption, as explained in the aforesaid patent.

To the forward end of the positive holder there is fixed an insulated nose cap 17. Pivoted to one side of the positive electrode and slightly in front of the crater thereof is an occulting disc or shield 18. Said disc may be made of highly refractory insulating material such as "transite" or other asbestos or mica compound, and is shown as mounted on a shaft 19 which, in turn, is rotatably mounted on the positive head. Said shaft may be rotated as by means of a gear 20 and rack bar 21, to throw the disc directly across the arc and in front of the positive crater, as shown in the dotted line position in Figs. 1 and 2. In this position the arc will be at once extinguished, and also the light from the glowing positive crater cut off from the reflector 22 which lies to the rear of the negative holder, as indicated in Fig. 1.

The rack bar may be readily operated from a distance by means of a comparatively high resistance or weak current solenoid 23 which, when energized, holds the rack down, as shown in Fig. 2, and the disc out of the arc, as illustrated in full lines. Said solenoid is preferably placed in a branch or independent weak current circuit controlled from a switch or button 38. If the current through the solenoid is broken by failure of the main supply or through button 38, the rack is drawn upwardly by means of the spring 24, thus revolving the disc into the dotted line position and extinguishing the arc and occulting the afterglow.

In order to also strike the arc quickly, I provide in conjunction with said disc an auxiliary striking electrode 25. Said electrode is shown as mounted in a two part steel and brass rod 26, 26' which extends within a solenoid winding 27 of heavy wires, through which the main arc current passes. Said solenoid is shown as having an interiorly tapered core, the bore flaring outwardly toward both ends, so as to contact with the rod 26 around a central circle 28. The rod is normally thrust forwardly by means of a compression spring 30 which rests at one end against the lamp structure or bracket 31 thereon, and at its outer end against a collar 32 fixed to the rod 26. The rod is shown as having a central ear 33 thereon, by which it is pivoted to an intermediate link 34 which, in turn, is pivoted to bracket 31 at 35. When, therefore, the rod is drawn to the right in Fig. 1 by the excitation of the solenoid, the tip of the electrode 25 will describe an arc 55

which is shown in dotted lines at 36, said arc running from the tip of the negative electrode 4, closely adjacent the tip of the positive electrode but preferably without touching the same, and then finally to the lower dotted line position illustrated at 25'. In case the main arc current should then be broken by the turning of the disc, the tip of electrode 25 will advance until it touches the disc 18, as shown in the dotted line position 25".

Referring to the wiring diagram, it will be seen that the main arc current passes at all times through solenoid winding 27 and that under the conditions shown in Fig. 1, current will pass through the rod 26 and auxiliary electrode 25 to the negative electrode 4, so that the arc will be struck and transferred to the larger positive electrode as the auxiliary electrode is drawn rearwardly. The weak current solenoid 23 therefore may be used to both light and extinguish the arc, and since it carries only a small current, it may be controlled from any distance through an auxiliary push button or snap switch 38. The operator at the lamp, by simply closing the main switch, may place the lamp in condition for operation, but the lighting and extinguishing may be entirely controlled from a distance through said auxiliary switch 38. Before the switches are closed, the parts will lie in the position shown in Fig. 4. When the main switch 39 is closed, the arc will not start because the switch 38 is not closed and solenoid 23 is unexcited, leaving the disc 18 in the position shown in Fig. 4. As soon, however, as the switch 38 is closed, the disc will be revolved to the full line position of Fig. 2 and the spring 30 will push the auxiliary electrode forwardly to contact with the negative electrode. The circuit thus closed will cause a heavy current to pass through solenoid 27, which will retract the auxiliary electrode, as explained, thus striking the arc. The arc will then remain lit until the switch 38 is opened, which will cause the disc 18 to turn across the arc and extinguish the same and the afterglow. At the same time the current will be broken through the solenoid 27 since the current therethrough depends upon the completion of the circuit between the positive and negative electrodes. The auxiliary electrode will then advance to contact with the disc 18 and be ready to advance into contact with the negative electrode upon removal of the disc by the closing of the button.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. A remote control for arc searchlights and the like, comprising a movable shield for extinguishing the arc, a movable auxiliary electrode for drawing the arc, an arc circuit winding for retracting the latter to draw the arc, and a weak current winding for controlling the position of said shield, said shield serving in its operative position to maintain said electrode in a retracted

position, whereby the arc may be quickly lighted and extinguished from a distance by controlling the excitation of said weak current winding.

2. A remote control for arc searchlights and the like, as claimed in claim 1, in which said shield in its occulting position lies in front of the said auxiliary electrode and prevents the latter from advancing to establish an arc until said shield is opened.

3. The combination with an arc lamp for searchlights, of an occulting disc, a pivotal mounting therefor, a spring biased winding for rotating said disc to cause it to lie across the arc and between the electrode tip, facing the reflector, and the reflector, and for rotating said disc to one side of the electrodes, and a branch circuit including a switch for exciting and de-energizing said winding, whereby the arc may be extinguished from a distance and afterglow prevented.

4. A remote control for arc searchlights and the like, comprising a movable shield for extinguishing the arc, a movable auxiliary electrode for drawing the arc from the negative to the positive electrode, means operable at will for moving said shield to either its occulting or in-effecting position, and spring opposed arc current responsive means for advancing said auxiliary electrode to touch the negative electrode when said shield is moved to its ineffective position and for withdrawing the same to draw the arc to the positive electrode.

5. A remote control for high intensity flaming arc lamps comprising a movably mounted auxiliary electrode for drawing the arc from the negative electrode to the positive electrode, spring opposed arc current responsive means for advancing said auxiliary electrode to touch the negative electrode and for then withdrawing the former past the positive tip to draw the arc, a movable stop for preventing the advance of said auxiliary electrode, and means operable from a distance for positioning said stop in its operative or inoperative position.

6. A remote control for high intensity flaming arc lamps as claimed in claim 5, in which said stop also acts as an arc extinguishing device.

7. A remote control for arc searchlights and the like, comprising a movable shield for extinguishing the arc, a movable auxiliary electrode for drawing the arc, an arc circuit winding for retracting said electrode to draw the arc, and a weak current winding for controlling the position of said shield and the advancement of said electrode, whereby the arc may be quickly lighted and extinguished from a distance by controlling the excitation of said weak current winding without interrupting the main supply.

8. A remote control for high intensity flaming arc lamps comprising a movably mounted auxiliary electrode for drawing the arc from the negative electrode to the positive electrode, spring opposed arc current responsive means for advancing said auxiliary electrode to touch the negative electrode and for then withdrawing the former past the positive tip to draw the arc, a two position refractory disc pivoted to one side of the arc, and adapted in one position to act as a stop for preventing the advance of said auxiliary electrode, and at the same time to lie between the positive and negative electrodes to extinguish the arc and in its second position to be inoperative, and means for rapidly extinguishing and lighting the arc by moving said disc from its inoperative to its operative position and return.

- 5 9. In a quick control device for arc searchlights, the combination with the spaced arcing electrodes, a movable occulting disc adapted in one position to lie across the arc between said electrodes to extinguish the arc and prevent afterglow, and a movable auxiliary electrode for drawing the arc, said disc in its occulting position lying in the path of said auxiliary electrode to prevent the latter from advancing to strike the arc until said disc is moved away.
- 10 10. The combination with an arc lamp for

search-lights having a pair of oppositely facing electrode holders and a reflector, the holder farther from the reflector facing the same, of an occulting disc of refractory material movably mounted on one of said holders, and means for moving said disc across the position normally occupied by the arc between the electrode holder facing the reflector and the other electrode holder near the reflector, whereby the arc is extinguished and the afterglow occulted.
